(57) **CLAIM**

The ornamental design for a wall-mounted AC charging pile, as shown and described.

DESCRIPTION

FIG. 1 is a front view of the wall-mounted AC charging pile; FIG. 2 is a rear view from thereof;

FIG. 3 is a left side view thereof;

FIG. 4 is a right side view thereof;

FIG. 5 is a top view thereof;

FIG. 6 is a bottom view thereof; and,

FIG. 7 is a perspective view thereof.

The broken lines shown in the drawings are included for the purpose of illustrating unclaimed portions of the wall-mounted AC charging pile and form no part of the claimed design.
